UNITED STATES PATENT OFFICE.

JOHN W. E. LAKER, OF VICTORIA, BRITISH COLUMBIA, CANADA.

HOLDER FOR SAFETY-RAZOR BLADES.

No. 922,296.

Specification of Letters Patent.

Patented May 18, 1909.

Application filed July 6, 1908. Serial No. 442,181.

To all whom it may concern:

Be it known that I, JOHN W. E. LAKER, a citizen of the British Empire, residing at Victoria, British Columbia, Canada, have invented certain new and useful Improvements in Holders for Safety-Razor Blades, of which the following is a specification.

This invention relates to improvements in devices for holding the blades of safety razors while they are being honed or stropped, and consists in certain peculiarities in the construction and arrangement of parts thereof and in certain novel combinations of elements substantially as hereinafter described and particularly pointed out in the subjoined claims.

The objects of the invention will be readily seen from the following description of the construction shown in the accompanying drawing, which illustrates what I at present regard as the best embodiment of my invention.

In said drawings: Figure 1 is a side view of my improved holder, showing a blade clamped in position therein for stropping or honing. Fig. 2 is a longitudinal section through the same. Fig. 3 is a section on the line 3 of Fig. 1. Fig. 4 is a view similar to Fig. 3, but showing the clamping members separated for the insertion or removal of a blade. Fig. 5 is a plan view of the implement with the movable jaw swung down to its full extent.

The same characters of reference designate the same parts in the several views.

My improved holder comprises four principal members as follows: a holder or chambered handle, a clamp having jaws which are located outside the handle and are movable relatively thereto, a spring-pressed adjusting means which has one end connected to the jaws and another end protruded from the handle for convenience in actuating it against its spring, and a locking means which holds the jaws in clamping position.

The handle A is preferably composed of wood, and formed with an opening extending entirely through it and closed at its rear end by a removable threaded bushing 2 having an aperture through which the jaws' adjusting device protrudes. The adjusting means for the jaws preferably consists of a straight rod or spindle 3 extending longitudinally through the opening 1 in the handle and a spring 4. This spring acts upon an abut-

ment 5 secured to the rod and tends to force the rod to its rearmost position, and hence serves to holding the clamping jaws 10 and 11 against accidental displacement from their locking means and also automatically to move said members into engagement with the same.

The locking means referred to is preferably in the form of a cap D which is removably secured, as by a pin 6, to the forward end of the handle and closes the same. This cap is formed with an aperture 7 into which the shanks 8 and 9 of the clamping jaws 10 and 11 extend and it co-operates with said shanks to hold the jaws against movement relatively to each other.

The jaws 10 and 11 are preferably formed integral with the shanks 8 and 9 and are expanded laterally beyond the same sufficiently to engage the entire blade, except the edge x of the same which is to be stropped or honed.

One of the jaws, as 10, has one of its edges formed with spaced lugs 12 which project from the longitudinal edge of the same, and the other of the jaws 11, has a longitudinal flange, 13, which extends into the space between said lugs and is pivoted thereto, as shown at 14. The jaws are thus hingedly connected along one longitudinal edge and their hingedly connected edges are, at the same time, well adapted to form the back of the implement upon which the same may be turned in stropping or honing in the same manner and with the same facility and advantages as in the case of stropping or honing an ordinary razor.

The jaws 10 and 11 are preferably made quite thin and are beveled from the backs toward their front edges. One jaw is formed with apertures 15 which are alined with those ordinarily formed in safety razor blades and the other jaw is formed with projections 16 which extend through the apertures in the blade and into the apertures 15 and thereby fix the blade against movement in the jaws.

In practice it is preferred, as shown, to form the fixed jaws 10, its shank 8 and the spindle 3 integral with each other, and to reduce the diameter of the metal at the junction of the spindle and shank to an extent equal to the thickness of the shank 9 of the pivoted jaw 11, as shown at 17, a shoulder being formed at the latter place 110

The spindle thus extends into the aperture in the locking-cap 5, and fills the inner side thereof. From the shank 8 the metal is thinned and widened to form the jaw 10. 5 This construction of jaw, shank and spindle may be economically produced.

From the foregoing the advantages of my invention will be understood, it being understood that a device constructed as herein set forth may be inexpensively produced, 10 will present a neat appearance, will be durable, may be most readily assembled and disassembled, will most effectively clamp a blade and while overcoming any tendency 15 of accidental loosening of the clamping action yet affords provision for convenient separation of the jaws when desired, and protects all portions of the blade except the edge which is being stropped or honed, and enables the stropping or honing operation to 20 be performed in the same manner as is practiced in the stropping or honing of ordinary or non-safety razors. It will also be apparent that the invention is not restricted 25 to the details illustrated and that many changes therein and many apparently widely different variations of the invention may be made without departing from the spirit of the invention or the scope of the subjoined 30 claims.

Having thus described the invention what I believe to be new and desire to secure by Letters Patent, is:—

1. A holder for a safety razor blade, comprising a handle, pivotally connected jaws, 35 means encircling the jaws for locking them together against pivotal movement, the jaws and their said encircling means having relative movement bodily, and means for producing such movement, comprising a rod 40 which is connected to the movable part and is adapted to move the same bodily in one direction and a spring which is connected to the rod and moves the movable part bodily 45 in the other direction.

2. A holder for a safety razor blade, comprising a chambered handle, jaws arranged outside said handle and pivotally connected with each other, a locking means for the jaws, and means for moving the jaws into and out 50 of engagement with the locking means, comprising a spindle arranged in the chamber in the handle and connected with the jaws and adapted to move the same in one direction and a spring which acts upon said spindle to 55 move the jaws in the opposite direction.

3. A holder for a safety razor blade, comprising a chambered handle having an apertured cap at one end, a longitudinally movable spindle arranged in said chamber and extending through said cap, a jaw connected to the other end of the spindle, a second jaw pivoted at its longitudinal edge to the longitudinal edge of the first jaw and provided with a shank to enter the aperture in the cap, and a 65 spring for pressing the spindle and jaws in one direction.

4. A holder for a safety razor blade, comprising a chambered handle having an apertured cap at one end, a jaw formed with a shank which extends into the aperture of 70 said cap and is provided with a rearwardly extending spindle which projects through the handle and is of greater thickness than the shank and jaw, and a second jaw mounted on 75 the first jaw and having a shank to enter the aperture in the cap, one of said jaws having spaced lugs projecting from its longitudinal edge and the other having a flange which extends from its longitudinal edge and is received by the space between said lugs, and means for pivotally connecting said flange and lugs together.

In testimony whereof I affix my signature in presence of two witnesses.

JOHN W. E. LAKER.
